UNITED STATES PATENT OFFICE.

EDWARD E. CLEMENT, OF WASHINGTON, DISTRICT OF COLUMBIA, ASSIGNOR TO THE NORTH ELECTRIC COMPANY, OF CLEVELAND, OHIO, A CORPORATION OF OHIO.

IMPULSE-TRANSMITTER FOR ELECTRIC SIGNALING SYSTEMS.

964,612.

Specification of Letters Patent. Patented July 19, 1910.

Application filed November 1, 1906. Serial No. 341,634.

To all whom it may concern:

Be it known that I, EDWARD E. CLEMENT, a citizen of the United States, residing at Washington, in the District of Columbia, 5 have invented certain new and useful Improvements in Impulse-Transmitters for Electric Signaling Systems, of which the following is a specification, reference being had therein to the accompanying drawing. 10 My invention relates to impulse transmitters for electric signaling systems, and especially to those intended to send groups of numbers.

It has for its object the production of 15 such a device which shall be reliable and efficient, economical both in its first cost and subsequent maintenance.

Briefly stated, the invention comprises a pair of contacts intended to be included in 20 an electrical circuit, a wheel or its equivalent having peripheral teeth adapted to work the contact springs, a motor for turning the wheel, and a number of setting devices associated with the wheel to determine 25 the number of impulses that will be effectively transmitted.

My invention is illustrated in the accompanying drawings in which—

Figure 1 is a front view of the complete 30 machine inclosed in a casing, Fig. 2 is a side view of the same, Fig. 3 is a side view of the mechanism with the casing removed, looking in the direction of the arrow in Fig. 1, Fig. 4 is a front view of the parts 35 shown in Fig. 3, Fig. 5 is a side view of the wheel removed from the other mechanism, Fig. 6 is an edge view of the same, Fig. 7 is a front view of the setting devices having the wheel shown in position between 40 them, and Fig. 8 is a side view of one of the setting devices.

Referring to Figs. 1 and 2, the mechanism is inclosed in a casing A having in its front a number of slots a , a' , a^2 , a^3 , and a^4 45 through which protrude the ends of the setting devices, provided with handles a^5 , a^6 , a^7 , a^8 and a^9 . Through one end of the casing a winding arbor b projects, carrying a crank with a handle b' for winding up the 50 spring of the motor.

The general operation of the device can be understood from Figs. 1 and 2 alone. It will be observed that each of the slots a , a' , etc., is provided with a number of notches a^{10} , 55 In practice I place a number opposite each

of these notches of which there are ten for each of the first four, and four for the last notch. With this arrangement it is possible to send any number from naught to 9,999 and one additional digit which may be used 60 for any special purpose, and which in the present case increases the range of selection four-fold, making it possible to transmit any one of forty thousand different arrangements of impulses. Thus, assume that we 65 wish to send the number 5647-2. The handle a^5 is moved down until its stem engages the fifth notch in the slot a . The handle a^6 is moved down until its stem engages the sixth notch in the slot a' . The handle a^7 is moved 70 down until its stem engages the fourth notch in the slot a^2 . The handle a^8 is moved down until its stem engages the seventh notch in the slot a^3 . The handle a^9 is moved down until its stem engages the second notch in 75 its slot a^4 . The crank of the arbor b is then turned as far as it will go, by means of the handle b' , and released. The mechanism inside then makes and breaks the circuit during one complete rotation of the main wheel, 80 the makes and breaks being divided into five groups with intervals between them, as follows: 5—6—4—7—2. After the wheel has made one revolution, the handle b' and 85 its crank have again reached their position of rest, and the mechanism stops. The same number may be sent over again by rewinding the motor spring, and so on indefinitely, as long as the setting handles are undisturbed. By resetting the handles, a new 90 number may be sent, of course.

The mechanism by which the foregoing results are attained is very simple, in fact only that shown in Fig. 7. It comprises the wheel W, having the peripheral teeth and five 95 ridges or short-circuiting flanges on its faces, coöperating with the setting or short-circuiting arms w , w' , w^2 , w^3 and w^4 , upon the ends of which are fixed the setting handles a^0 , a^8 , a^7 , a^6 , a^5 , to which reference 100 has already been made. The wheel W is fastened to but insulated from the shaft m , which is journaled in two side plates, m' and m^2 , of the casing. This shaft is driven by a spring motor of the type employed in 105 clock works, toys, messenger call boxes, and the like. The motor consists of a spring driving arbor b connected to the main spring b^2 , which drives a train of gears connected to the shaft m , the motion of which is regu- 110

lated or retarded by means of the escape-
ment b^3 and verge rod and weight b^4 . When
the handle b' is turned, the spring is wound
up and when the handle is released, the
5 wheels of the motor, together with the shaft
 m , will turn sufficiently to rotate the wheel
 W completely once. At the end of this rotation,
10 the stop mechanism b^5 in the motor maintains all the parts in position. Further
description of the motor is unnecessary, and
in fact I may state here that the type of
motor employed is immaterial and may be
varied at will without departing from my
15 invention at all.

15 The essential and characteristic elements
embodying my invention are shown in Fig.
7, removed from the rest of the apparatus.
The principle upon which they operate is
this: Each of the handles a^5 , a^6 , etc., corre-
20 sponds to one of the sets of teeth on the
wheel, and each corresponding arm comes
into play at the moment that its set of teeth
is passing over the contact spring s . A pro-
jection is provided on the wheel for each
25 arm, that is to say radially opposite each set
of teeth, and this projection or flange will
reach and make contact with the end of the
arm after an angular movement determined
by the angle through which the arm has
30 previously been moved in setting it. Thus,
if in setting, the arm has been moved for-
ward the space of five teeth, then five teeth
will pass over the spring s before the pro-
jection on the wheel reaches the arm. As
35 soon as it does reach the arm, the springs are
short-circuited through the frame and al-
though the rest of the teeth in that set may
continue to pass over the springs, their ac-
tion thereon is nullified and the circuit main-
40 tained closed until the set of teeth and pro-
jecting flange have completely passed, to-
gether with the interval before the next set
of teeth reaches the spring pen s .

Referring to Figs. 3 to 7, I have marked
45 the projecting flanges on the wheel as w^5 ,
 w^6 , w^7 , w^8 and w^9 . Of these, two, w^5 and w^6 ,
are upon one side of the wheel, and three,
 w^7 , w^8 and w^9 , are upon the other side or
face of the wheel. The wheel is intended
50 to rotate in the direction of the arrow in
Fig. 5, and it should be stated here that
Fig. 7 is a view from beneath the wheel and
arms, or looking in the direction of the arrow
55 in Fig. 3. The flanges are placed at
different radial distances from the center
and the ends of the arms w , w' , etc., are bent
over at corresponding radial distances, so
that each flange, as the wheel turns, will en-
gage its own arm and no other. Thus, it
60 will be apparent that in each rotation of the
wheel every arm will be touched once by its
flange and will pass along the same through-
out its length, thus making metallic contact
between the arm and the wheel. For the
65 arm w , this contact is made with its flange

w^9 when the teeth w^{90} are passing over the
spring s ; for the arm w' , it is made with
its flange w^8 when the teeth w^{80} are passing
over the spring s , and so on. As the handles
70 a^5 , a^6 , etc., are moved, they move the other
ends of the arms, which are pivoted on a
brass sleeve of the shaft m , so that the move-
ment of the ends of the arms is on the same
center as that of the wheel.

In Fig. 4, which is the mechanism com-
plete with the casing removed, the arms w ,
 w' , w^2 , w^3 and w^4 are shown upstanding
75 with their handles removed. In Fig. 8 the
arm w^4 is shown in side view looking in the
direction of the arrow in Fig. 7. The arms 80
are pivoted upon a sleeve of the central
shaft m and are separated from each other
by nuts, w^{10} and w^{11} , and washers, w^{12} .

The spring s' is connected with the frame
through the overlying plate s^2 and the screws
85 s^3 . The spring s on the other hand is insu-
lated, and these springs are normally in
contact as shown in Fig. 3 so as to complete
the electric circuit 1, 2, 3, containing the
battery D and the electromagnet E. I show
90 this circuit with the battery and the electro-
magnet merely for the purpose of making
the invention clear.

95 My invention is particularly applicable to
automatic telephone exchange systems, in
which the connections between subscribers'
lines are made by mechanism at the central
office controlled through impulses sent either
from the subscribers' or from the operators'
positions at central.

100 I contemplate employing the present send-
ing machine in what I have called semi-auto-
matic telephone systems of my own design,
in which there are operators at the central
office to answer incoming calls from sub-
scribers' lines, and who then set up the
105 numbers wanted on these machines, each
machine being started by means of its handle
 b' when set, after which the operator need
pay no further attention to the connection
thus effected. The impulses from the ma-
chine in such case go to the trunk upon
which the calling subscriber is connected,
and thence to the automatic selector switches
110 which are also connected thereto, causing said
switches to select the line wanted in the
usual way. In these systems to which I have
referred, the circuit of the sending machine
is normally closed and the magnet E holds
its armature normally attracted as indicated
115 in the drawing. As the wheel rotates, the
springs s and s' are caused to make and
break the circuit through their contact, until
the arm corresponding to the set of teeth
passing is reached by its projecting flange
120 on the wheel, when the springs are imme-
diately short-circuited, by the following
path: From wire 1 to the spring s , to the
wheel, through the teeth with which it comes
125 in contact, to the flange, to the arm in con-
130

tact with the flange, to the frame, to the screws s^3 , the strip s^2 , the spring s' , and wire 2. The reasons for insulating the wheel will now be perceived. It serves as an intermediate short-circuiting member between the arms, that is to say the frame, and the spring s . As an example of a number to be transmitted, I suggested 5647-2. The setting of the handle a^5 was explained and I will now point out how this affects the arms corresponding to the handles. The first arm was moved around a distance of five teeth, the second a distance of six teeth, the third a distance of four teeth, the fourth a distance of seven teeth, and the fifth a distance of two teeth, all from normal or zero position, which is indicated in Fig. 3. If the box was started by winding the spring while the arms were in the positions shown in Figs. 3 and 4, no number would be transmitted at all, because the first tooth would no sooner touch the spring s than the flange w^5 would touch the arm w^4 . With the arms moved around, however, as I have indicated, five teeth of the set w^{60} must pass over the spring s before the flange w^5 reaches the arm w^4 ; six teeth of the set w^{60} must pass over the spring before the flange w^6 reaches its arm, and so on.

Having thus described my invention specifically, I desire it to be well understood that many changes may be made in its embodiment and more of application without departing from the essential and characteristic features.

I intend to use the device either upon the operator's desk at the central office in connection with trunk lines and signals whereby the operator may control automatic switches, or at a subscriber's station where it is particularly valuable because it can be applied to any standard telephone circuit, requiring only a single connection to the pair of springs s , s' , and enabling the subscriber to see at a glance what was the last number he called for, also to call for that number over again without resetting if he so desires. The box may be used in many other places, however, such as fire alarm systems, as a telegraph transmitter, for police purposes and the like. Its range of numbers is very great, and it only requires the extension of the slot a^4 so as to provide for ten numbers like the others (the teeth on the wheel being all provided with that number) to enable 100,000 different arrangements or combinations of impulses to be transmitted.

Having thus described my invention what I claim and desire to secure by Letters Patent is:

1. An impulse transmitter comprising a number wheel and a coöperating impulse device, a contact moving with the wheel throughout its impulse transmitting period,

and a coöperating adjustable contact separate from the wheel adapted to be set so as to maintain operative circuit conditions for any predetermined number of impulses only.

2. An impulse transmitter comprising a motor, a number wheel driven thereby, a spring contact controlled by the wheel and a short circuiting device for the spring contact, said device being adjustable to act when the wheel is at different points in its rotation, to thereby determine the number of impulses to be transmitted.

3. In an impulse transmitter, a motor, a number wheel, a contact device governed thereby, and a plurality of short-circuiting devices coöperating with the wheel to determine different numbers of impulses to be transmitted.

4. In an impulse transmitter, a motor, a number wheel having a plurality of groups of teeth separated by plain intervals, a contact device adapted to be operated by said teeth to make and break an electric circuit, and a number of adjustable disabling devices corresponding to the number of groups of teeth, each coöperating with the wheel during the passage of its corresponding group of teeth over the contact device so as to determine the number of impulses to be transmitted from that group.

5. An impulse transmitter comprising a motor, a signal wheel having a plurality of groups of teeth, a circuit controlling device coöperating with said groups of teeth, and a plurality of adjustable short-circuiting devices, one for each group, adapted to be set so as to shunt the circuit controlling device after any desired number of teeth in the group have passed thereover whereby the number of impulses to be transmitted may be determined.

6. In an impulse transmitter, a motor, a number wheel having a plurality of operating segments separated by plain or idle segments, a contact device controlled by said operating segments, a projecting flange opposite each segment, said flanges being at different radial distances from the center, a plurality of contact arms pivoted concentrically with said wheel, each of a proper length to reach one of the flanges, and means for setting said arms and retaining them in position when set, the wheel being insulated from the rest of the mechanism except when in contact with the arms or the contact device, the whole arranged so that each operating segment will transmit a number of impulses determined by the angular distance through which its corresponding flange must pass before reaching its arm, and being thereafter short-circuited.

7. In an impulse transmitter, a motor, a toothed wheel having a plurality of segments, a contact device coöperating with the teeth, and adjustable means engaging said

segments for rendering the contact device inoperative during the passage of one or more teeth.

8. A variable signal impulse transmitter having a transmitting wheel adapted to send a predetermined total number of impulses, and a short circuiting device adjustable to engage the wheel in its rotation so as to prevent the transmission of any desired number of said impulses.

9. A variable signal impulse transmitter having an impulse signal transmitting wheel, and a plurality of short-circuiting devices coöperating therewith.

In testimony whereof I affix my signature in presence of two witnesses.

EDWARD E. CLEMENT.
